US00D855173S

(12) **United States Design Patent** (10) **Patent No.:** **US D855,173 S**
Cegla (45) **Date of Patent:** **** Jul. 30, 2019**

(54) **INHALER**

(71) Applicant: **R. CEGLA GMBH & CO. KG,**
Montabaur (DE)

(72) Inventor: **Ulrich Cegla**, Montabaur (DE)

(73) Assignee: **R. CEGLA GMBH & CO. KG,**
Montabaur (DE)

(**) Term: **15 Years**

(21) Appl. No.: **35/502,850**

(22) Filed: **Oct. 24, 2016**

(80) **Hague Agreement Data**

Int. Filing Date: **Oct. 24, 2016**

Int. Reg. No.: **DM/094674**

Int. Reg. Date: **Oct. 24, 2016**

Int. Reg. Pub. Date: **Apr. 28, 2017**

(30) **Foreign Application Priority Data**

May 4, 2016 (EM) 003109909-0001

(51) **LOC (11) Cl.** **29-02**

(52) **U.S. Cl.**

USPC **D24/110**
